CLAIM

The ornamental design for a home computer housing and display support, as shown and described.

DESCRIPTION

FIG. 1 is a perspective view of a home computer housing and display support showing our new design; FIG. 2 is a side elevational view thereof on an enlarged scale, the opposite side being a mirror image; FIG. 3 is a rear elevational view thereof on an enlarged scale;

FIG. 4 is a front elevational view thereof on an enlarged scale;

FIG. 5 is a bottom plan view thereof on an enlarged scale;

FIG. 6 is a rear perspective view of a home computer housing and display support showing our design.

*FIG. 1.**FIG. 2.*

FIG. 3.

FIG. 4.

FIG. 5.

FIG. 6.
